(57) **CLAIM**

The ornamental design for an enteral feeding tube proximal end, as shown and described.

DESCRIPTION

FIG. 1 is a front, left perspective view of an enteral feeding tube proximal end according to the design.

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The features shown in broken lines depict environmental structure only and form no part of the claimed design.
